UNITED STATES PATENT OFFICE

WALTER N. VAN FLEET, OF BOONTON, NEW JERSEY, ASSIGNOR TO SHARP & VAN FLEET MANUFACTURING CO., INC., A CORPORATION OF NEW JERSEY

BOILER

Application filed June 6, 1927, Serial No. 196,847. Renewed September 19, 1930.

An object of the present invention is to provide a boiler so constructed that steam may be generated therein within a comparatively small amount of time, and upon the heating of only a small quantity of the water contained in the boiler.

In the ordinary boiler construction, the water which is first heated effects a general circulation in the water chambers of the boiler and substantially the entire body of water must be heated before steam may be drawn off.

In accordance with the present invention, the boiler is preferably provided with a relatively thin crown sheet of water communicating by a vertical upflow pipe with a steam chamber, the end of the upflow pipe being arranged well above the water level, and the pipe being of such cross sectional area that the boiling water therein will not bubble over. By virtue of this construction, the main body of water in the boiler is substantially inert, and as steam passes from the top of the upflow pipe, a corresponding amount of water will flow into the bottom of the crown sheet inlet from a suitable reservoir. The device is in effect a dead water boiler with no circulation of water occurring except such circulation as is necessary to replace the water which has boiled off as steam.

Other objects of the invention are to provide a boiler of simple, practical construction which will be rugged, durable and efficient in use, and well suited to the requirements of economical manufacture and operation.

With the above noted and other objects in view, the invention consists in certain novel features of construction and combinations and arrangements of parts, as will be more fully hereinafter set forth and pointed out in the claims. The invention may be more fully understood from the following description in connection with the accompanying drawings, wherein—

Fig. 1 is a transverse vertical sectional view through a boiler constructed in accordance with the present invention.

Fig. 2 is a longitudinal vertical sectional view therethrough on the line 2—2 of Fig. 1.

Figs. 3 and 4 are sectional plan views on

the lines 3—3 and 4—4 respectively of Fig. 1.

Fig. 5 is a fragmentary vertical sectional view illustrating a slight modification in which the boiler is used in connection with a hot water instead of a steam system.

Many details of the boiler mounting, water level regulating means and similar structural details having no particular bearing on the present invention have been omitted for the sake of clarity, and I have illustrated simply the water chambers, firebox and flue spaces.

In the drawings I have used the reference numeral 10 to designate the hollow front wall of the boiler, and the reference numeral 11 to designate the hollow rear wall thereof. Wall 10 is provided with a lower water space 10a below the fire door 12 and with an upper water space 10b above the fire door. Corresponding water chambers 11a and 11b are provided in the rear wall, this wall simply being open at suitable points to communicate with the flue outlet 13, and to provide a cleaning opening 14.

The hollow side walls 15 of the boiler are also filled with water and communicate with the front and rear walls through passages 16. Bridging the firebox 20 are crown chambers 21 into which water from the hollow side walls of the boiler flows. To enter the crown chambers from the side water spaces, the water must flow around the lower ends of depending partition-forming aprons 22 arranged in the side water spaces and terminating near the lower ends of the latter.

Also connecting the side water spaces at a series of points above the crown chambers 21 are horizontally extending water chambers 23.

Rising from each crown chamber 21 is a vertical pipe 24 provided with an enlarged upper end 25 terminating well above the water level in the boiler and opening into a steam chamber 26 provided with any suitable number of steam off-takes 27. The cross sectional area of the pipes 24 is sufficient to prevent any percolator effect, or in other words, any water boiling out of the upper ends of the pipes, but the diameter of the pipes 24 is less than the cross sectional area of

the chambers 23, so that pipes 24 pass directly through chambers 23.

A water inlet such as the pipes 30 from a header 31 may be controlled in any suitable manner to maintain a constant water level within the boiler, this level being disposed well below the enlarged outlet end 25 of the pipe 24 as above suggested.

It will be noted that a series of units each consisting of side water chambers, crown chambers 21, pipe 24 and cross chamber 23 are arranged side by side, so that the boiler is substantially a built-up construction, and the flow through the various sections is through the openings 16 above described. Obviously these sections might be unconnected for water flow and separate water inlets might be provided for all of them if desired.

In operation, the water flows into the water spaces 23 downwardly into the hollow front and side walls of the boiler, around the lower ends of the aprons 22, filling the crown sheets and the pipes 24 until the desired water level is reached.

The heat transmitted to the water in the crown sheets and crown chambers 21 is of course much more intense than the heat directly transmitted to any other parts of the boiler. In consequence, long before the rest of the boiler water is heated, steam will be escaping from the upper ends of the pipes 24 and passing out through the outlets 27. The water which leaves the pipes 24 in the form of steam, is replaced by water flowing into the crown chambers around the lower ends of the partitions or aprons 22. Thus, the main body of water in the boiler is substantially inert, the flow being only sufficient to maintain a constant water level and to replace the water which is lost in the form of steam.

It will be noticed that the side water chambers within the hollow walls 15 also communicate with the common steam chamber 26 in order to prevent any possibility of steam being trapped in the system when all of the water in the boiler is hot.

By arranging the crown chambers 21, the side chambers, and the cross chambers 23 as separate units and spacing them slightly apart, the hot flue gases may flow between the various sections and transmit heat directly to the water in all of the cross chambers and side chambers. The arrangement of such flue passages is best seen in Fig. 2, wherein it will be noted that substantially all of the water chambers of the boiler are exposed on all sides to the heat of the hot gases from the firebox and a very large effective heating surface is had.

In Fig. 5 I have illustrated a slight modification of the invention in which the boiler is used for circulating hot water, and in which pipes 24a corresponding to the pipes 24 communicate directly with hot water upflow pipes

40 and hot water return pipes 41 enter the upper chamber 26a of the boiler. In this system of course, the entire boiler including the chamber 26a will be filled with water and water circulation may be very quickly induced by highly heating the water in the crown sheets, causing it to circulate upwardly through the pipes 24a.

Obviously, various changes and alterations might be made in the general form and arrangement of the parts described without departing from the invention. Hence I do not wish to limit myself to the precise details set forth, but shall consider myself at liberty to make such changes and alterations as fairly fall within the spirit and scope of the appended claims.

I claim:

1. A boiler including a firebox, water spaces at the front and side walls of the firebox, a top steam chamber communicating with the water spaces and having a steam outlet, crown chambers extending across the top of the firebox and connecting the side water spaces, said crown chambers communicating with the side water spaces only at the lower ends of the latter, vertical pipes rising from the crown chambers and terminating in the steam chamber well above the water level in the boiler, said pipes being of sufficient cross sectional area to prevent the hot water from boiling out of the top thereof and communicating with the water in the boiler only through the crown chambers.

2. A boiler including a firebox, water spaces at the front and side walls of the firebox, a top steam chamber communicating with the water spaces and having a steam outlet, crown chambers extending across the top of the firebox and connecting the side water spaces, said crown chambers communicating with the side water spaces only at the lower ends of the latter, vertical pipes rising from the crown chambers and terminating in the steam chamber well above the water level in the boiler, said pipes being of sufficient cross sectional area to prevent the hot water from boiling out of the top thereof and communicating with the water in the boiler only through the crown chambers, the side water spaces including vertical partitions terminating near their lower ends and around which water must flow from the side water spaces to reach the crown chambers.

3. A boiler including a firebox, water spaces at the front and side walls of the firebox, a top steam chamber communicating with the water spaces and having a steam outlet, crown chambers extending across the top of the firebox and connecting the side water spaces, said crown chambers communicating with the side water spaces only at the lower ends of the latter, vertical pipes rising from the crown chambers and terminating in the steam chamber well above the water level in

the boiler, said pipes being of sufficient cross sectional area to prevent the hot water from boiling out of the top thereof and communicating with the water in the boiler only through the crown chambers, a plurality of transversely extending water chambers connecting the side water spaces above the crown chambers.
